UNITED STATES PATENT OFFICE.

ROY V. COLLINS, OF NEW YORK, N. Y., ASSIGNOR, BY MESNE ASSIGNMENTS, TO
ROYAL ENGINEERING CORPORATION, A CORPORATION OF NEW YORK.

SWITCH-THROWING MECHANISM.

1,152,791.

Specification of Letters Patent.

Patented Sept. 7, 1915.

Application filed November 10, 1911. Serial No. 659,485.

To all whom it may concern:

Be it known that I, Roy V. Collins, a citizen of the United States, and a resident of the borough of Manhattan of the city of New York, in the county and State of New York, have invented certain new and useful Improvements in Switch-Throwing Mechanisms, of which the following is a specification.

10 The invention relates to mechanism and apparatus which may be applied to an electrically operated railroad whereby a switch point is under the control of a motorman operating the car.

15 The mechanism which is the subject of the present invention comprises two main features, namely, a line contactor which is placed adjacent to and connected with a trolley wire, or other source of electrical supply, and a street box containing therein a plurality of solenoids for operating the switch point. The line contactor is electrically connected with the solenoids in the street box in such a manner that when a car 20 is passing along the trolley wire and has a member in engagement with the contactor at a time when only a comparatively small amount of current or no current at all is being withdrawn by said car from the trolley wire, the switch point will be thrown to a certain position if not already in said position and when a large quantity of current is being withdrawn for the purpose of propelling the car the switch point will automatically be thrown to another certain position if not already in said position.

25 The invention also relates to a line contactor which is particularly adapted for use on an overhead trolley wire of a railway system and it furthermore relates to the particular construction of a line contactor which will automatically close a circuit when a trolley wheel is moving along in engagement therewith at a time when a small amount or no current is being utilized on the car and which is so constructed that another circuit will be completed when the trolley wheel is moving along in engagement therewith when a large amount of current for operating the car is being utilized.

As showing a specific embodiment of the invention, reference is made to the draw-

ings forming a part of this specification and in which—

Figure 1 shows an assembled view of the line contactor and the street box containing the solenoids which are operatively connected to the switch point. It also shows the wiring extending between the line contactor and the solenoids in the street box. Fig. 1^a is a partial side view of the contactor showing the position of the contacts for completing the circuit through one of the solenoids in a street box. Fig. 1^b is a partial side view of the contactor showing the position of the contacts for completing the circuit through the other solenoid in the street box. Fig. 2 is a plan view, partially broken away, of the line contactor. Fig. 3 is a broken side view, mostly in section, of the "leaving end" of the contactor with the trolley wire in place relative thereto. Fig. 4 is a side view partly in section of the "approach end" of the contactor. Fig. 5 is a section taken on the line 5—5 of Fig. 4, the trolley wheel being located in broken lines in both Figs. 4 and 5. Fig. 6 is a section taken on the line 6—6 of Fig. 3 looking in the direction of the arrows, the upper inverted T-shape portion shown in said figure being a portion of the main frame, the portion having the arc shaped bottom being the movable section of a pivoted lever and the part having a circular cross section being the trolley wire. Fig. 7 is a view taken on the line 7—7 of Fig. 3 looking in the direction of the arrows.

The trolley wire or source of supply is indicated by the reference character 1 while the switch point to be operated is indicated by the reference character 2. In Fig. 1 the switch point is shown extending in a direction 90° from that in which it normally extends merely for the sake of clearness and for the purpose of including the transverse section of the street box and the side view of the contactor in the same figure.

The line contactor indicated by the reference character 3 comprises a main frame 4, a pair of stationary contacts 5 and 6, a movable contact 7, a pivoted lever 8, means between the movable contact and the frame and between the movable contact and the free end of the pivoted lever whereby when the latter is raised the movable contact will

be thrown into engaging position with one or the other of the stationary contacts and contact selecting or controlling means 10 which determines whether the movable contact will or will not engage a certain one of the stationary contacts when the lever is moved the proper distance. The frame 4 may be connected with the trolley wire in any well known manner as by the parts 11 and 11'.

The pivoted lever 8 preferably comprises two main portions or sections, namely, an insulated portion at the "approach end" of the contactor (which in some devices embodies forms of the invention may not necessarily be movable) and a movable portion. This movable portion as shown in applicant's construction is not insulated from the trolley wire since it directly engages members that are electrically connected to said wire but in carrying out applicant's invention, it is immaterial whether or not the freely movable portion is insulated. The insulated portion 12 is pivotally connected at one end to a bearing 13 that is insulated from the frame by insulating material at 13^a and 13^b and at its other end there is carried the freely movable part 14 which is insulated from the section 12 by the insulating material 15. The parts 12 and 14 together constitute the lever which is pivoted at 16 on bearing 13 and the outer or free end of this lever when in the lowest position is supported by connecting mechanism, extending between it and the movable contact, which in turn is supported on the frame. The insulated portion 12 of the lever is shown enlarged in cross section in Fig. 5. In said figure it will be observed that the trolley wire 1 and the insulated section 12 are so positioned relative to each other that the trolley wheel during its engagement with and travel along the latter, will be forced away from the trolley wire a sufficient distance to break the direct flow of electricity from the wire to the wheel. The approach end of this insulated section is provided with an incline which causes the trolley wheel to gradually move from the wire without an appreciable shock. This incline is clearly shown in Figs. 1 and 4 and is designated by the reference character 12^a.

In Fig. 6 a section of the frame 4 is shown and between it and the trolley wire 1 is positioned the movable section 14. This latter section is arc shaped on its lower side and is provided with a removable steel wearing strip 14^a secured to the section 14^b which is the part of the movable part or portion 14 that is secured to but insulated from the insulated section or part 12. The free end of the lever is so constructed that while it normally will rest in its lowest position it can be readily pushed upward by

a trolley wheel when passing along under and in engagement therewith whereby one of the circuits to the solenoids in the street box will be closed.

Contacts 5 and 6 are carried by but insulated from the frame 4 and between them but not normally in contact with either of them there is located the movable contact 7. This contact is provided with a pin 17 that enters a slot 18 in the link 9 which is pivotally connected to the frame at 19, the link serving as a movable means for normally supporting the contact on the frame. Said movable contact is also electrically connected to the trolley wire by a connection 20^a extending between the pin 17 on the contact and the frame 4 with which the trolley wire is electrically connected. The free or outer end of the pivoted lever, namely the movable portion above referred to, is provided with a slot 20 (see Figs. 3 and 7) in which there is secured by means of the bolt 21 and nut 21^a an adjustable vertical finger 22 the upper end of which is pivotally connected at 23 to the lower portion of the movable contact 7. It will thus be apparent that when the movable portion or the free end of the pivoted lever is raised the lower portion of the movable contact will be pushed upward and since the pivotal portion 17 is located on a movable link support the contact 7 will be free to move. When the contact selector or controlling means 10 is not operated and remains in the position shown in Fig. 3 the upper portion of the movable contact will always move to the right or in engagement with stationary contact 5 when operated by the movable portion. This position of the contacts is clearly shown in Fig. 1^b.

The contact selector or controlling member 10 comprises a solenoid 24 which operates the pointed plunger 25. This plunger is normally held in retracted position by the spring 26 but when actuated it assumes the forward position shown in Fig. 1^a and engages the laterally projecting finger 27 which is on the lower part of the movable contact 7. This engagement of the plunger 25 with the finger 27 causes the upper portion of the movable contact to be thrown from its normal position to the left a sufficient amount whereby when said contact is forced to move by the movable portion of the pivoted lever it will swing to the left around that portion of the finger 27, as an instantaneous center, which is in engagement with the plunger 25. Thus when the free end of the pivoted lever or the movable section is raised while the plunger 25 is in forward position the upper end of the movable contact 7 will be thrown to the left and an electrical connection will be completed by the engagement of said contact 7 with the stationary contact 5. This position of

105

110

115

120

125

130

the contacts is clearly shown in Fig. 1^a. One terminal of this solenoid or magnet 24 in the contact selecting or controlling means is electrically connected to the insulated portion of the pivoted lever while the other terminal of said solenoid is electrically connected to the frame 4 and thus to the trolley wire.

In order that the effect of current required or necessary to operate the contact controlling plunger 25 which is actuated by the movable member 24' of the solenoid or magnet may be under control there is provided an adjustable screw stop 24''. As this screw stop regulates the position of the movable member 24' which is within the coil of the solenoid or magnet 24, it will be apparent that the effect of the current to operate said movable member against the pressure of the spring 26 may be varied by either positioning the movable part 24' toward or from the magnet. When a car passes under the line contactor with the trolley wheel in engagement with the pivoted lever thereof at a time when the power is off or only sufficient on the car to provide for the purposes of heating and lighting, the solenoid 24 will not operate the plunger 25 and the movable contact 7 will be free to and will be moved to the right. When current is on the car sufficient in amount to operate the same it will be drawn from the trolley wire through said solenoid 24 thence through the insulated portion of the pivoted lever to the trolley wheel thence to the car. This current is sufficient to cause the solenoid to force the plunger 25 forward to such position whereby the upper end of the movable contact will be moved to the left when the free end of the pivoted lever is raised, and said movable contact will thus complete a circuit by engagement with contact 5.

From an inspection of the drawings it will be observed that contact 5 is electrically connected with one of the solenoids 26' in the street box by the wiring 26^a while contact 6 is electrically connected with solenoid 26^b in the street box by the wiring 26^b. These solenoids are arranged so that when the current is passed by means of the movable contact 7 to contact 5 and from thence through solenoid 26' and finally to the ground the switch point will be thrown in one direction and so that when the circuit is completed through the movable contact 7 and the stationary contact 6 through solenoid 26^b and from thence to the ground the switch point will be thrown in the opposite direction.

The operating of the switch throwing mechanism is as follows: If the motorman desires to go in a certain direction he merely cuts off the car operating current when approaching a switch point. Now when the car passes under the line contactor the free

end of the pivoted lever will be lifted by the upward thrust of the trolley wheel during its engagement therewith. This upward movement of the free end of the lever will operate the movable contact 7 and complete a circuit through one of the solenoids (26') to the ground and thereby throw the switch point to the proper position if not already in said position and if the switch point is already in said position it will be merely held tighter against the rail while the trolley wheel is in contact with the pivoted lever. Should the motorman however desire to go in a different direction he merely allows a car operating current to pass through the car motor at the time when the trolley wheel is passing under the line contactor. When he does this the engagement of the trolley wheel with the inclined insulated portion at the approach end of the contact will cause the trolley wheel to be pushed from contact with the trolley wire and as all the car operating current which passes to the trolley wheel from the insulated portion must first pass through the solenoid of the contact controlling means it will necessarily be operated thereby, and thus coöperate with the movable contact 7 so that the free end of the pivoted lever will force the movable contact into engagement with another contact whereby a circuit is completed through another solenoid (26^b) arranged to throw the switch point in the proper position if not already in said position. It will therefore be observed that the contact engaging member 25 operates only when the car is drawing operating current from the insulated portion of the line contactor and that when no car operating current is being used the upper end of the movable contact 7 will always be moved to the right by the trolley wheel lifting the free end of the pivoted lever. But when operating current is being supplied to the car the contact controlling solenoid will move the movable contact to such position that when the free end of the pivoted lever is raised it will force the upper end of the movable contact to the left thus completing a different circuit from that which is completed when it is forced to the right.

The street box previously referred to is formed of two parts separated by a horizontal water-tight partition 27. Through this partition there extends a vertical shaft 28 provided with a depending flange 29 that enters into the mercury 30 contained in a sealing cup 31. It will be observed from an inspection of Fig. 1 that the top of the sealing cup 31 extends above the bottom 32 of the switch point and also that this cup extends above the partition. This has been constructed in this manner in order to prevent the switch point from forcing dirt into the cup and also in order to form a wall around said shaft which will prevent the

tendency of dirt or mud on or above the partition from drifting or settling into the cup.

It is obvious that various forms and modifications may be made without departing from the spirit and scope of the invention.

5 I claim as my invention:

1. A line contactor having a frame which is adapted to be connected with a trolley wire, said frame carrying at its approach end an insulated section, and a movable section located adjacent to the leaving end of the contact, said frame supporting a contact controlling means comprising a magnet, one terminal of which is adapted to be electrically connected to a supply wire and the other end of which is electrically connected with the insulated section, said frame also carrying two contacts, a movable contact operated by the movable section, the aforementioned contacts, movable section and contact controlling member so constructed, arranged and operated that when a substantial or large current is being passed through the magnet of the contact controlling means the 25 circuit will be completed by a movement of the movable member due to engagement of the movable contact with one of the contacts on the frame and so that when a lesser current or no current at all is passing through said magnet the movable section will cause engagement between the movable contacts and the other contact carried by the frame thereby completing a second circuit.

30 2. The combination of a line contactor comprising a frame, a supply wire connected therewith and a trolley member, said frame supporting between it and the supply wire, a pivoted lever having at the approach end thereof an insulated section, the movable or free end of the lever being at the leaving end of the contactor the cross section of the approach end which is insulated being so shaped and positioned relative to the trolley wire that the trolley wheel when in engagement therewith will be moved out of engagement with the trolley wire, said frame carrying two stationary contacts and a controlling means for a movable contact, said 45 controlling means being electrically connected to the supply wire and to the insulated section and the movable contact being operated by the pivoted lever the movable contact being moved into engagement with 50 one of the stationary contacts on the frame at one time and in engagement with the other stationary contact at another time, the movement of the movable contact into engagement with a particular contact being dependent 55 upon the controlling means carried by the frame.

60 3. A line contactor having a frame, a pivoted lever comprising an insulated portion, a contact which is moved by the lever when it is moved, an electrical selector comprising

a magnet, one terminal of which magnet is electrically connected to the trolley line when the contactor is in place the other terminal of which is connected to the insulated portion, the electrical selector so constructed and arranged that when current is passing to the magnet thereof to supply the operating current for a car the selector will coöperate with the lever and movable contact whereby the latter may be moved to one position by the lever, the lever and movable contact so arranged that the latter will be moved by the former to another position when car operating current is not passing through the magnet.

70

75

80

4. A line contactor having a frame to be secured to a trolley wire, a trolley wheel engaging portions insulated from the frame, a trolley wheel engaging portion movable relative to the frame, a selector comprising electrically operated means having one terminal to be electrically connected to the supply wire and the other to the insulated portion whereby when current for operating the car is being drawn therethrough the electrical means will operate the selector to regulate the position of a contact and means operated by the movable portion to close a circuit.

85

90

95

5. A line contactor having a frame, means for securing the frame to a trolley wire, a member insulated from the frame, a vertically movable member, a contact adapted to be mechanically operated by the last mentioned member, an electrical means having one terminal electrically connected to the supply wire, the other to the insulated member carried by the frame, and circuit controlling means comprising said electrical means.

100

6. A line contactor having a pivoted lever comprising a portion insulated from the frame and a freely movable portion which moves a contact to engage other contacts, the line contactor having a magnet for determining when a certain circuit is to be completed by movement of the contact into engagement with one of said contacts, said magnet being electrically connected to the supply wire and insulated section.

105

7. The combination of a frame, a movable portion carried thereby, two contacts connected to but insulated from the frame and a third contact coöperative with the frame and movable portion so that it normally is located between and not in contact with either of the other contacts, a contact selecting or controlling means and a pair of solenoids; the parts constructed and arranged so that where permitted to do so by the selecting means the movable contact will always be moved into engagement with a certain one of the contacts by the movable portion when it moves and so that when not permitted to do so by the said selecting or

110

115

120

125

130

controlling means the movable contact will be moved into engagement with the other stationary contact by the movable section when it moves; one of the solenoids being 5 electrically connected to one of the stationary contacts, the other solenoid being electrically connected to the other of the stationary contacts, and the movable contact being electrically connected to the trolley 10 wire.

8. In a line contactor a frame to which may be secured a trolley wire, a vertically movable section carried by said frame, two contacts on said frame, a movable contact 15 operated by said movable section and normally held from engagement with the first-mentioned contacts and an electrical selector which, when operated, will cause the movable section, when moved, to effect engagement 20 between the movable contact and one of the first-mentioned contacts, the movable contact so mounted that when the electrical selector is not operated the movable contact will be moved to engagement with the other 25 first-mentioned contact by the movable section when it moves in the same direction as before.

9. A line contactor having a frame, a movable trolley wheel engaging section, contacts 30 at least part of which are carried by the frame, one of which contacts is moved by the section, a solenoid having a plunger to engage a portion which is movable with the last mentioned contact, the movable contact 35 being supported by a member movable on the frame said movable contact having a connection between it and the movable section whereby when the latter is in its lowest 40 position the movable contact will be out of engagement with any other contact.

10. In a device of the class described, a

trolley wire, a double solenoid, a controlling magnet, a movable conductor and means for supporting the same adjacent to the trolley wire, a contact member which may be controlled by said controlling magnet, contacts 45 in the double solenoid circuits which may be closed by the pressure of a trolley wheel on said movable conductor through one coil of the double solenoid, or by the combined 50 action of the controlling magnet and trolley wheel through the other coil of the solenoid when the device is in use, so that when a motor current is shut off from the motors of a car one of the coils of the double sole- 55 noid will be energized and when the motor current is applied to the motors of a car the other coil of the double solenoid will be energized.

11. In a device of the class described, a 60 trolley wire, a movable insulated conductor and means for supporting the same adjacent to the trolley wire, a controlling magnet which is connected to the trolley wire and said movable conductor, a double solenoid 65 adapted to operate the switchpoint and means actuated by the combined action of said controlling magnet and the movable conductor or by the movable conductor alone so that when a trolley wheel presses on this 70 movable conductor, a circuit will be closed through one or the other of the coils of the double solenoid according to whether or not a motor current is drawn through the trolley 75 wheel when on the movable conductor.

This specification signed and witnessed this 9th day of November A. D., 1911.
